RIVETING DEVICE

Paul H. Irmischer, Chicago, Ill.

Application October 4, 1946, Serial No. 701,249

4 Claims. (Cl. 78—53)

1

This invention relates to certain new and useful improvements in a riveting device and has for its principal object the provision of an improved construction of this character which will be highly efficient in use and economical in manufacture.

Among the several objects of the invention is a riveting device which is substantially portable in character; that is, the same may be attached to drill presses of different types and construction without modification of either the drill press or the riveting device.

A still further object of the invention is the provision of a riveting device which is capable of being handled and operated in the most economical and expeditious manner.

Another object of the invention is the provision of a riveting device having provision for connection to a standard drill press or the like.

Another object of the invention is the provision of a riveting device which comprises relatively few parts and which may be assembled in the most economical and expeditious manner.

Another object of the invention is the provision of a riveting device which has provision for reducing the noise created by its operation.

A further and equally important object is the provision of a riveting device which is substantially self-lubricating.

A still further object of the invention is the provision of a riveting device having an adjustable peen tool whereby two members may be tightly riveted together or loosely riveted together as the case may require.

Other objects will appear hereinafter.

The invention consists in the novel combination and arrangement of parts to be hereinabove described and claimed.

The invention will be best understood by reference to the accompanying drawings showing the preferred form of construction, and in which:

Fig. 1 is a perspective view of the riveting device embodying my invention;

Fig. 2 is a vertical sectional detail view of the same;

Fig. 3 is an expanded view illustrating the relationship of the several parts of the riveting device embodying my invention;

Fig. 4 is a fragmentary prospective view of a standard drill press illustrating my riveting device associated therewith;

Fig. 5 is a fragmentary sectional detail view showing the relationship of the peening tool with respect to a rivet at the start of the riveting operation;

2

Fig. 6 is a similar fragmentary sectional detail view but showing the riveting operation completed;

Fig. 7 is a perspective view of a form of peening tool adapted to be associated with the tool holder embodied in my invention; and

Fig. 8 is a fragmentary sectional detail view of the end of said peening tool.

The several objects of my invention are accomplished by the preferred form of construction as shown in the accompanying drawings.

In this connection, a holding member in the form of a ring-like member is indicated at 10. This ring-like member 10 comprises a web 11 providing, together with the walls 12 of the ring on opposite sides of the web 11, sockets 13 and 14. The web 11 is provided with a centrally located opening 15 and projected through this opening 15 is the cylindrical body 16 of a base cap 17 having a depending boss 18. In this base cap 17, with the major portion thereof located in the boss 18, is a socket 19. Projected in this socket 19 is the shank 20 of a peen tool holder 21. This shank 20 is removably secured in the socket 19 by a set screw 22. The peen tool holder 21 has a centrally located bore 23 formed therein and in this bore 23 the peen tool 24 is adjustably mounted, the latter being fixed in a predetermined adjusted position by means of a set screw 25. The end 26 of the peen tool 24 is provided with a plurality of peen prongs 27, of which there may be any number.

The base 17 has a circular lateral flange 28 which operates in the socket 14. Between this flange 28 and the web 11 and within the socket 14 is a sound-absorbing ring 29 formed of any suitable and desirable material.

Formed in the top portion of the cylindrical body 16 is a ring-like groove 30. Projecting from the bottom wall 31 of this groove 30 and fixed to the cylindrical body 16 are connecting pins 32. An upper cap portion 33 is provided with a marginal lateral ring-like flange 34. This flange 34 provides, together with the cap 33, a recessed portion 35 into which projects the upper end portion of the cylindrical body 16. The flange 34 projects into the socket 13. The cap 33 is provided with spaced openings 36, into which project the pins 32.

The cap 33 provides a centrally located sleeve 37. Projecting through this sleeve 37 is the shank 38, which has a reduced outer end portion 39 threaded into the cylindrical body 16. The shank 38, exterior of the sleeve 37, provides an enlarged head 39' and this head 39' has a predetermined

spacing from the adjacent end portion of the sleeve 37 and is of a diameter less than the outside diameter of the sleeve, the space being sufficient to permit relative movement of the upper and lower caps 33 and 17 relative to the ring 10 for riveting operation but not sufficient to permit caps 33 and 17 to escape from ring 10.

On the web 11 are mounted trip buttons 40, there being in the present instance three of such buttons; however, the number of the same may vary. These buttons 40 are tapered in a direction substantially at right angles with respect to a radius line drawn from the cylindrical body 16 so that the taper will be downwardly in the direction of rotation of the caps 33 and 17.

The flange 34 of the cap 33 carries trip buttons 41 tapered in an opposite direction to the taper of the buttons 40, there being as many such trip buttons 41 as there are buttons 40.

Formed in the ring 10 is a threaded socket 42 and threaded in this socket 42 is a lubricating cap 43 adapted for attachment to the nozzle of a grease gun in a well known manner. Communicating with this socket 42 is a passage 44, through which the lubricant finds its way into the opening 15 for passage between the several moving parts of the device.

In Fig. 4, I have illustrated a well known and standard drill press, to illustrate the manner in which my riveting device may be associated therewith. In this connection, the drill press, as shown in Fig. 4, includes a post 45 and a rotatable chuck 46 and a work table 47, the latter adjustably carried by the post 45.

The chuck 46 is rotated in the usual and well known manner and is of a construction well known in the art.

It is with such a drill press, or one similar thereto, that my riveting device is adapted to be associated. This is accomplished by inserting the sleeve 37 into the chuck 46 to which chuck 46 it will be attached in a well known manner. To prevent rotation of the ring 10 with the chuck 46, I provide a handle 48 and this handle 48 is adapted to bear against the post 45 in the manner shown in Fig. 1.

When the chuck 46 is rotated, the caps 33 and 17 will be rotated therewith, the ring 10 and web 11 being held against rotation by engagement of the handle 48 with the post 45. As the caps 33 and 17 are rapidly rotated, the trip buttons 40 and 41 will have rapid contact with each other and by virtue of their tapered engaging surfaces will move the cap 33 upwardly away from the base cap 17 against the pull of the operator's arm on bar 50 as the buttons 41 pass over the buttons 40, and as buttons 41 pass beyond buttons 40, cap 33 will drop to rapidly impinge the peen tool 24 in rivet head forming operation.

The chuck 46 is supported by a rotating shaft 49 comprising a part of the standard drill press and movable in the direction of its length, by means well known in the drill press art including a handle 50. In this manner the peen tool 24 is brought down upon the stock or rivet shank for forming the head thereon.

If two members such as 23' and 24', Figs. 5 and 6 are to be tightly riveted together by a rivet 25', as shown in Figs. 5 and 6, the peen tool 24 is adjusted to its extreme outer position relative to the sleeve 37. On the other hand, if the two members are to be loosely riveted together, then the peen tool 24 is adjusted within the sleeve 37, a distance sufficient to produce the loose rivet

connection. Such distance may vary according to the looseness desired.

From the foregoing description, it is apparent that I provide a riveting device which is substantially portable in character, capable of attachment or association with the chuck of a standard and well known drill press, one that comprises few parts and is capable of economical production and highly efficient in use.

While I have illustrated and described the preferred form of construction for carrying my invention into effect, this is capable of variation and modifications without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A riveting device comprising a base member having a socket formed therein and an oppositely disposed cylindrical boss, a peen tool holder mounted in said socket, a peen tool mounted in said holder, a holding member having a wall portion provided with a central opening for the reception of said boss, trip buttons on said wall and having top surfaces tapered in a direction substantially at right angles with radial lines through said boss, a cap mounted in said holding member, trip buttons on said cap and having surfaces tapered in a direction opposite to the tapered surfaces of the first mentioned trip buttons and adapted for engagement with said tapered surfaces of said first mentioned trip buttons, a sleeve on said cap, a stud screw projected through said sleeve and threaded into said boss and having an enlarged head on one end thereof spaced a limited distance from said sleeve and cooperating with said sleeve to limit the relative movement of said base member and said cap with respect to each other by the engagement of the trip buttons on said wall with the trip buttons on said cap, and means for connecting said base and said cap together for limited movement relative to each other by action of the engagement of the tapered surfaces of said trip buttons.

2. A riveting device comprising a base member having a socket formed therein and an oppositely disposed cylindrical boss, a peen tool holder mounted in said socket, a peen tool mounted in said holder, a holding member having a wall portion provided with a central opening for the reception of said boss, trip buttons on said wall and having top surfaces tapered in a direction substantially at right angles with radial lines through said boss, a cap mounted in said holding member, trip buttons on said cap and having surfaces tapered in a direction opposite to the tapered surfaces of the first mentioned trip buttons and adapted for engagement with said tapered surfaces of said first mentioned trip buttons, a sleeve on said cap, a stud screw projected through said sleeve and threaded into said boss and having an enlarged head on one end thereof spaced a limited distance from said sleeve, means for connecting said base and said cap together for limited movement relative to each other by action of the engagement of the tapered surfaces of said trip buttons, and a sound absorbing member disposed between said wall and a flange of said base.

3. A riveting device comprising a base member having a socket formed therein and an oppositely

disposed cylindrical boss, a peen tool holder mounted in said socket, a peen tool mounted in said holder, a holding member having a wall portion provided with a central opening for the reception of said boss, trip buttons on said wall and having top surfaces tapered in a direction substantially at right angles with radial lines through said boss, a cap mounted in said holding member, trip buttons on said cap and having surfaces tapered in a direction opposite to the tapered surfaces of the first mentioned trip buttons and adapted for engagement with said tapered surfaces of said first mentioned trip buttons, a sleeve on said cap, a stud screw projected through said sleeve and threaded into said boss and having an enlarged head on one end thereof spaced a limited distance from said sleeve, means for connecting said base and said cap together for limited movement relative to each other by action of the engagement of the tapered surfaces of said trip buttons, said peen holder having an opening formed therein in which said tool is mounted and said tool being adjustable relative to said holder, and means for securing said tool to said holder in a predetermined adjusted position.

4. A riveting device comprising a base member having a socket formed therein and an oppositely disposed cylindrical boss, a peen tool holder mounted in said socket, a peen tool mounted in said holder, a holding member having a wall portion provided with a central opening for the reception of said boss, trip buttons on said wall and having top surfaces tapered in a direction sub-

stantially at right angles with radial lines through said boss, a cap mounted in said holding member, trip buttons on said cap and having surfaces tapered in a direction opposite to the tapered surfaces of the first mentioned trip buttons and adapted for engagement with said tapered surfaces of said first mentioned trip buttons, a sleeve on said cap, a stud screw projected through said sleeve and threaded into said boss and having an enlarged head on one end thereof spaced a limited distance from said sleeve, means for connecting said base and said cap together for limited movement relative to each other by action of the engagement of the tapered surfaces of said trip buttons, a sound absorbing member disposed between said wall and a flange of said base, said peen holder having an opening formed therein in which said tool is mounted and said tool being adjustable relative to said holder, and means for securing said tool to said holder in a predetermined adjusted position.
